Howson and Howson

UNITED STATES PATENT OFFICE.

FREDERICK BERNARD BROWN, OF CHESTER, ENGLAND.

INTERNAL-COMBUSTION ENGINE.

Application filed March 9, 1927, Serial No. 173,971, and in Great Britain March 9, 1926.

This invention relates to internal combustion engines of the kind comprising a cylinder (hereinafter referred to as the main cylinder) having slidable therein a sleeve, or 5 sleeves, within which sleeve, or within the inner sleeve of which the piston of the engine reciprocates and also having a movable head, constituted by longitudinally slidable plunger which acts, at the proper time, in conjunction 10 with the piston of the engine to effect the discharge of spent, or inert gases, remaining from the ignition and combustion of previous charges, and this invention has for its object to provide an improved engine of the afore- 15 said kind which is more efficient in operation and in which the said spent, or inert gases, are practically wholly discharged.

According to this invention, the head of the main cylinder of the engine is constituted 20 by an auxiliary cylinder of smaller diameter than that of the said main cylinder. The auxiliary cylinder may have a part which extends within the main cylinder of such external diameter that a space is provided between the exterior of the said part and the interior of the said main cylinder for the accommodation of the valve sleeve, or sleeves, of the engine. Reciprocal within the said auxiliary cylinder is a plunger which is 25 moved outwards when the compression space is to be left free for the compression of a charge and moved inwards when the said compression space is to be occupied by the said plunger when exhaust is taking place, these 30 movements being effected positively in both directions preferably by a crank driven from the engine shaft at half engine speed. The charge of explosive mixture in the compression space is ignited by a sparking plug which 35 communicates with the auxiliary cylinder at any suitable part thereof.

I will more particularly describe my invention with reference to the accompanying drawing in which Figures 1 and 2 shew, in 40 sections, at right angles to each other, so much of a four cylinder engine as is necessary to illustrate the invention and also to shew the relative positions of the main and auxiliary pistons of the engine at each cycle of 45 operation. In the following description reference is made only to one of the four cylinders shewn in the drawing.

Referring to the figures, 1 indicates the main cylinder of the engine which is shewn 50 surrounded by a water-jacket 2; 3 and 4 two concentric valve sleeves, slidable within the

said main cylinder, having inlet and exhaust ports 5 and 6 which communicate, at the proper times, with inlet and exhaust ports 7 and 8, respectively, in the wall of the said main cylinder, 9 the piston reciprocal in the said sleeve 4 and 10 the piston rod connected to the main crank shaft of the engine, all of which is adapted to operate in the known manner. The head 11 of the main cylinder 1 is shewn as having integral therewith a water-jacketed auxiliary cylinder 11^a of less diameter than that of the main cylinder 1 and as having a part 11^b which extends within the said main cylinder, the external diameter of 70 the said extension being such that a space 12 is provided between it and the wall of the said main cylinder for the accommodation of the valve sleeves 3 and 4.

The extension 11^b of the head 11 may be 75 provided with a ring, or rings, such for example as shewn at 11^c to ensure a gas-tight joint between the said extension and the inner sleeve 4. Reciprocal within the auxiliary cylinder 11 is a plunger 13 which is 80 moved outwards when the compression space 14 is to be left free for the compression of a charge of explosive mixture and moved inwards when the said compression space is to be occupied by the said plunger when exhaust 85 is taking place. Any suitable means may be provided for positively effecting the movements of the plunger 13 at the proper times, for example, the said movements may be effected by a crank 15 driven from the engine 90 shaft at half engine speed.

The charge of explosive mixture in the compression space 14 is ignited by a sparking plug 16 secured in a passage or channel, 17 in communication with the interior of the 95 auxiliary cylinder 11^a constituting the said compression space.

In the arrangement shewn as each piston 9 descends for the suction stroke the inlet port 7 is opened and the explosive charge drawn in 100 until the said piston is at, or towards, the lower end of the inner sleeve 4 when the said port is closed, the plunger 13 being then towards the bottom of the auxiliary cylinder 11^a as shewn at A Figure 1. The piston 9 and the 105 plunger 13 then ascend in their respective cylinders, the said piston forcing the explosive mixture out of the inner sleeve 4 into the auxiliary cylinder 11^a where it is compressed in the compression space 14. At the end of 110 this compression stroke the piston 9 is at, or towards the upper end of the inner sleeve 4

and the plunger 13 is at, or towards, the upper end of the auxiliary cylinder 11^a as shewn at B Figure 1. Firing of the explosive mixture is then effected and at the end of the firing, or working, stroke the plunger 13 would still be towards the upper end of its cylinder 11^a when the piston 9 is at, or towards, the lower end of the inner sleeve 4, as shewn at C, Figure 1. At the next stroke of the engine the piston 9 and the plunger 13 advance towards each other and force the products of combustion through the now open exhaust port 8. At the end of this exhaust stroke the piston 9 will be at the upper end of the inner sleeve 4 and the plunger 13 at the lower end of its cylinder 11^a as shewn at D Figure 1, there then being such space, shewn at 14^a, between the upper surface of the piston 9 and the under surfaces of the head of the cylinder 11 and the plunger 13, sufficient only to allow for the necessary working clearance between them.

It is to be understood that the invention is not limited to the precise details of construction, or arrangement, of the parts hereinbefore described and shewn as it is obvious that modifications may be made without departing from the scope of the invention, for example, the auxiliary cylinder instead of being made integral with the head 11 may be constituted by a sleeve, or liner, suitably secured in the said head of the main cylinder of the engine, and also, it will be understood that the invention is applicable for use in engines having any desired number of cylinders.

What I claim is:—

1. In an internal combustion engine a main cylinder having movable therein a valve sleeve, within which sleeve the piston of the

engine reciprocates, the said sleeve being provided with inlet and exhaust ports which control inlet and exhaust passages in the said cylinder, in combination with an auxiliary cylinder in the head of the main cylinder, said auxiliary cylinder having a part which extends within the said main cylinder, and is of such external diameter that a space is provided between the exterior of the said part and the interior of the said main cylinder for the accommodation of the valve sleeve of the engine, and an auxiliary piston reciprocable within said auxiliary cylinder for varying the combustion space.

2. In an internal combustion engine of the kind referred to having in the head of the main cylinder of the engine an auxiliary cylinder with a part which extends within the said main cylinder the said part having a water-jacket within the main cylinder, and an auxiliary piston reciprocable within said auxiliary cylinder for varying the combustion space.

3. In an internal combustion engine of the kind referred to having in the head of the main cylinder of the engine an auxiliary cylinder with a part which extends within the said main cylinder, said auxiliary cylinder constituting the explosion chamber, and having a sparking plug secured in a passage, or channel, in communication with the interior of the said auxiliary cylinder, and an auxiliary piston reciprocable within said auxiliary cylinder for varying the combustion space.

In testimony whereof I have signed my name to this specification.

FREDERICK BERNARD BROWN.
